UNITED STATES PATENT OFFICE.

CHARLES W. WOLF, OF LIMA, OHIO.

COMBINATION MEGAPHONE AND HORN.

No. 914,472.

Specification of Letters Patent.

Patented March 9, 1909.

Application filed August 6, 1908. Serial No. 447,256.

To all whom it may concern:

Be it known that I, CHARLES W. WOLF, a citizen of the United States, residing at Lima, in the county of Allen and State of Ohio, have invented certain new and useful 5 Improvements in a Combination Megaphone and Horn, of which the following is a specification.

My invention relates to sounding toys, 10 and its object is the provision of a megaphone and a horn so combined that either may be used, and whereby when the horn is used, the megaphone will be caused to amplify the sound of the horn, and when the 15 horn is not used, it will remain secured to the megaphone and not interfere with the use of the megaphone, but at the same time will be ready for convenient application thereto when desired.

20 My invention consists in a megaphone, and a horn or other sound producing instrument movably secured thereto, as well as in the parts and in the details of construction and arrangement of parts, as will hereinafter be 25 more fully described and claimed.

In the drawing: Figure 1 is a side elevation of a device embodying my invention. Fig. 2 is a horizontal sectional view, enlarged, on a line corresponding to the line $x-x$ of Fig. 1, 30 the horn being represented as turned away from the mouth piece of the megaphone. Fig. 3 is a view similar to Fig. 2, the horn being represented as applied to the mouth-piece of the megaphone. Fig. 4 is a horizontal section of part of a megaphone provided with a reversible mouth piece, and thus embodying a modification of my invention. Fig. 5 is a detail perspective view 35 of the horn and the plate on which it is mounted. Fig. 6 is a horizontal section of part of a megaphone embodying my invention as I prefer to construct it. Fig. 7 is a horizontal section of part of a megaphone embodying another modification of my invention. Fig. 8 is a cross section on a line 40 corresponding to the line $y-y$ of Fig. 7. Figs. 9 and 10 are horizontal sections of megaphones embodying other modifications of my invention.

50 As illustrated in Figs. 1, 2 and 3 of the drawing, the megaphone preferably comprises a shell or main part 1 of frusto-conical formation, on the smaller end of which is provided a mouth piece 2. The shell 1 may 55 be composed of any thin light material, such

as tin plate or paper. The mouth piece 2 may be constructed of metal, and is of formation adapted to conform to the smaller end of the shell of the megaphone so that it will fit tightly thereon, and may be secured 60 in any suitable manner. In this construction the mouth piece 2 does not flare at its opening, but is merely provided with a roll rim 3, so that it will be smooth and not injure the mouth when applied thereto. 65 This mouth piece 2 has an opening 4 in it at one side, closely adjacent to the rim 3, and a plate 5, of circular formation to conform to the opening of the mouth piece 2, has a lug or extension 6 which is bent around to form 70 a hook adapted to be hooked through the opening 4 in the mouth piece. Thus, the plate is hinged to the mouth piece, and may be applied thereto like a lid, or may be turned away therefrom, leaving the mouth 75 piece open for the application of the mouth. Substantially in the center, this plate 5 has an opening through which the horn 7 passes and which horn is permanently secured therein. This horn 7 is tapered, and is so 80 mounted in the plate 5 that when the plate 5 is applied to the mouth piece 2, the small end of the horn is presented outwardly and the greater part of the horn is outside, while the larger end extends slightly inward past 85 the plate 5. This tapering horn 7 is provided interiorly with a pipe 8 and a reed 9 positioned in the usual manner, and the horn may be inserted into the mouth for blowing 90 through it, to vibrate the reed and produce 95 the sound. When the plate 5 with the horn 7 mounted therein is thus applied to the mouth piece 2, and the horn is blown through, the sound produced by the vibration of the reed 9 will be amplified by the megaphone comprising the shell 1, this shell 1 thus constituting a bell for the horn 7. Then, when it is not desired to use the horn 100 and it is desired to use the megaphone in the usual manner for merely amplifying the voice, the plate 5 may be swung around, bringing the horn 7 in a substantially reversed position at the side of the mouth piece 2, so that it will not interfere with the application of the mouth to the mouth piece 2. 105

As illustrated in Figs. 1, 2 and 3, the metal mouth piece may be permanently secured to the shell 1, but, as illustrated in Fig. 4, the mouth piece 2^a may be removable from the shell 1^a and may flare in both 110

directions from its middle, both the flaring parts thus formed being adapted to fit tightly on the small end of the shell 1^a. Then one of the ends of the mouth piece 2^a 5 may be provided with a roll rim 3^a, while it may be provided near the other end with an opening 4^a, on which the plate 5^a may be hinged by means of the lug or extension 6^a. This plate 5^a carries the horn 7^a and is sub- 10 stantially like the plate 5 carrying the horn 7, as illustrated in Figs. 1, 2 and 3. Thus provided with a reversible mouth piece, when it is desired to use the horn, the end of the mouth piece 2^a may be applied to the 15 shell 1^a and the plate 5^a may be swung over the other end of the mouth piece 2^a, as above described in connection with the construction illustrated in Figs. 1, 2 and 3. When it is not desired to use the horn, the plate 5^a 20 may be swung away from the end of the mouth piece, allowing the small end of the shell 1^a to be inserted in this end and leaving the other flaring end with its roll rim 3^a presented for the application of the mouth. 25 Thus the horn 7^a is more completely removed than it is in the use of the construction illustrated in Figs. 1, 2 and 3.

My invention is constructed as illustrated in Figs. 1, 2 and 3 with the mouth piece 2 30 permanently secured to the shell 1 and tapering substantially continuously therewith, in order that one of the devices will readily fit inside another one, so that they may be nested closely for transportation. For the 35 same reason the plate 5, carrying the horn 7, may be detached from the mouth piece 2 in shipping, it being convenient to merely insert the lug 6 of the plate 5 into the opening 4 of the mouth piece 2 and bend it 40 around to form the hinge for the horn 7. Where the mouth piece 2^a is removable and reversible, as illustrated in Fig. 4, the plate 5^a may be permanently hinged to the mouth piece 2^a and the mouth pieces may be re- 45 moved from the shells, thus allowing the shells to nest more compactly.

While the constructions above described are particularly convenient for handling during transportation, I prefer to construct my 50 improved combination megaphone and horn as illustrated in Fig. 6 of the drawing, where the shell 1^b is provided with a permanently secured flaring mouth piece 2^b, to which is hinged the plate 5^b carrying the horn 7. 55 Preferably, this mouth piece 2^b is made of wood while the plate 5 and horn 7 are constructed of tin plate, the horn 7 being soldered into the opening in the plate 5. This plate 5 may be so hinged to the mouth piece 60 2^b by means of its lug 6, passing through the opening 4^b, that it may be removed for transportation as hereinbefore described.

In the modification of my invention illustrated in Figs. 7 and 8, a mouth piece 2^c is at- 65 tached to a shell 1^c, both the mouth pieces

and shell being similar to the mouth piece 2^b and shell 1^b illustrated in Fig. 6. However, the mouth piece 2^c is provided with a slot 10, extending half-way around it close to the termination of the shell 1^c where the shell is 70 inserted in the mouth piece, and a plate 11 of sufficient thickness to almost fill the slot 10 and slide therein is hinged by means of a lug 12, near one of the terminations of the slot 10, by means of the pin 13 inserted in the 75 mouth piece, substantially parallel to the length of the device. Thus the plate 11 is so hinged that it will be allowed to swing edge-wise into alignment with the interior opening of the mouth piece, or entirely out of the interior opening as may be desired. This plate 11 is provided with another lug 14, which extends past the outside of the mouth piece 2^c when the plate 11 is swung into alignment with the interior thereof, this lug 80 14 being provided for engagement by the thumbs or finger for moving the plate 11. This plate 11 carries a suitable reed 15 mounted over a slot 16 in the plate 11, the reed being adapted to be vibrated by blowing into the mouth piece 2^c when the plate 11 is in alignment with the interior thereof. Then, when it is desired to use the megaphone for merely amplifying the voice, the plate 11 may be swung entirely out of the interior of the mouth piece 2^c as illustrated. 85

In the construction illustrated in Fig. 9, the mouth piece 2^d is mounted on a shell 1^d, the mouth piece 2^d being preferably made of wood, a plate 5^d and horn 7^d, preferably also 90 of wood and of integral formation, are applied to the mouth piece 2^d by pivotally mounting the plate 5^d, on the mouth piece by means of a pin 17. This allows the plate 5^d to be swung edgewise, carrying the horn 100 7^d out of the way of the mouth piece 2^d when it is desired to apply the mouth to the mouth piece. The horn 7^d is provided interiorly with a pipe 8^d and a reed 9^d substantially similar to the pipe 8 and reed 10 in the horn 110 7 illustrated in Figs. 1, 2 and 3 of the drawing.

When it is desired to use a whistle in conjunction with the megaphone, the megaphone may be constructed with a shell 1^e and 115 a mouth piece 2^e, preferably of wood, which mouth piece 2^e has slots 18 and 19 extending radially through its walls and diametrically opposed to each other. The whistle is of substantially circular formation and, having 120 a flattened mouth piece 21, is mounted in the mouth piece 2^e by means of a lug 22, which extends into one of the slots 18 and is secured by means of the pin 23 which is inserted into the mouth piece 2^e across the slot 18. The 125 whistle 20 has another lug 24, which is adapted to extend through the slot 19, passing outside of the mouth piece 2^e when the whistle 20 is in position in the interior of the mouth piece, this lug 24 being provided for the en- 130

gagement of the thumb and finger to move the whistle 20. Thus constructed, when it is desired to use the whistle 20 in conjunction with the megaphone, it may be swung into 5 the mouth piece 2^e and the lips may be applied to the whistle, the megaphone serving to amplify the sound thereof. Then, when it is not desired to use the whistle but to use the megaphone for merely amplifying the 10 voice, the whistle may be swung outside the mouth piece into such position that it will not interfere with the application of the mouth to the mouth piece.

Both the tin horn and the megaphone are 15 highly desirable instruments for use in producing a noise in public demonstrations, and the combination of the two instruments in one allows both economy of construction and convenience in use. At the same time the 20 effect of the horn is greatly increased by using it in conjunction with the megaphone, while the usefulness of the megaphone is in nowise impaired by the union of the horn therewith. By movably securing the horn, 25 or other sound producing instrument, to the megaphone, the liability of misplacing the sound producing instrument, when it is not used in conjunction with the megaphone, is avoided, and it is maintained in position for 30 the most convenient application of it to the megaphone when it is desired, it being only necessary, with the use of the constructions illustrated in Figs. 1, 2, 3 and 6 of the drawing, to shake the megaphone in the proper 35 direction with one hand to effect the application of the horn to the mouth piece of the megaphone or to remove it therefrom, the horn swinging on its hinged connection by merely partaking of the motion imparted to 40 the megaphone. The megaphone thus having the horn or other sound producing instrument secured thereto is also particularly suitable as a toy for children, who will quickly 45 lose a small article that is completely detached from a larger one, owing to the pre-

dominant impression made by the larger article.

From the above description, it will be evident that my invention is capable of considerable modification without departure from 50 the scope and spirit thereof.

I claim:

1. As a new article of manufacture, a combination megaphone and horn comprising a megaphone having one end smaller than the 55 other end, and a sound producing instrument hinged to the smaller end, substantially as and for the purposes specified.

2. As a new article of manufacture, a combination megaphone and horn comprising a 60 megaphone, having one end smaller than the other end and having a mouth piece on the smaller end, and a sound producing instrument hinged on the mouth piece, whereby it may be applied to the mouth piece or turned 65 away to give access to the mouth piece, substantially as and for the purposes specified.

3. As a new article of manufacture, a combination megaphone and horn comprising a megaphone having a shell with one end 70 smaller than the other end, and a mouth piece secured to the smaller end adapted to receive the mouth for talking through the megaphone, and a sound producing instrument comprising a plate hinged to the mouth 75 piece and a horn passing through the plate and carried thereby, provided with a reed interiorly thereof, the horn being adapted to be brought into alinement with the megaphone so that its sound may be amplified and being 80 adapted to be moved out of alinement with the megaphone, to allow the mouth to be applied to the mouth piece of the megaphone substantially as and for the purposes specified.

CHARLES W. WOLF.
